UNITED STATES PATENT OFFICE.

ARCHIBALD S. TELFER, OF HOUSTON, TEXAS.

CENTRIFUGAL PUMP.

Application filed March 17, 1922. Serial No. 544,670. Renewed September 4, 1923.

To all whom it may concern:

Be it known that I, ARCHIBALD S. TELFER, a citizen of the United States, residing at Houston, in the county of Harris and State 5 of Texas, have invented certain new and useful Improvements in a Centrifugal Pump, of which the following is a specification.

This invention relates to new and useful 10 improvements in a centrifugal pump.

One object of the invention is to provide an attachment which will prevent the liquid being pumped from leaking out along the impeller shaft and being wasted.

15 Another object of the invention is to provide an attachment of the character described, which is of very simple construction, and consequently which may be cheaply and easily manufactured and readily applied to the pump.

With the above and other objects in view the invention has particular relation to certain novel features of construction, operation and arrangement of parts, an example 25 of which is given in this specification and illustrated in the accompanying drawings, wherein:—

The figure shows a side view partially in section of a centrifugal pump.

30 Referring now more particularly to the drawing, the numeral 1 designates the casing, as a whole. Rotatably mounted in this casing there is the impeller shaft 2, to which the impeller blades 3 are secured. By the 35 rotation of these blades the fluid is drawn into the inlet chamber 4 and forced from said chamber into the discharge chamber 5 and thence discharged through the discharge outlet. The impeller shaft is provided with suitable packing rings as 6, at 40 each side of the casing, which are confined by means of suitable glands 7, 7.

In operating centrifugal pumps it is often necessary to use a liquid seal to prevent the 45 leakage of air, and also to keep the pump cool. To provide for this liquid seal suitable sealing rings as 8 are employed, one on each side of the impeller, and lines 9 lead from the discharge chamber 5 to the 50 sealing rings through which liquid is delivered to said rings at approximately the discharge pressure of the pump. The liquid seals around the shaft are thus provided. Liquid coming through the lines 9 55 has a tendency to leak along the shaft in each direction, part of it finding its way

back into the volume of fluid being pumped and the rest working along the shaft in the other direction past the packing rings 6, and leaking out and being wasted. To minimize 60 the leakage of the fluid past the packing 6, I have provided an attachment which will now be described, the parts hereinbefore referred to being of conventional form and common to centrifugal pumps. 65

Just outside of the sealing rings 8, I have located an inside and an outside washer 10 and 11. These washers are spaced apart and they fit closely within the bore of the casing and fit snugly on the shaft 2 so as to provide as small amount of clearings as possible for the leakage of the fluid past them. Between these washers there is located a ring 12 provided with a clearance 70 between it and the shaft and also between 75 it and the wall of the bore in the casing. This ring has a plurality of radiating bores 13 through it.

Connecting the suction and discharge chambers of the pump are the pipes 14, 14. 80 I have provided the suction lines 15, 15 whose inner ends register with the respective rings 12. The outer ends of the suction lines 15 are fitted through the respective pipes 14 and are overturned toward the inlet, or suction chambers 4 and are formed into contracted discharge nozzles 16. The pipes 14, just beyond the nozzles 16 are contracted as at 17 to give a stronger suction, giving the effect of an ejector, thus drawing the liquid 90 which is leaked along the shaft through said suction pipes 15 and discharge it into the pipes 14 through which it will find its way back into the chamber 4 and practically none of the liquid will work on along the 95 shaft past the packing 6.

In order to have this ejector effect the pipes 14 will receive their liquid at the pressure equal to the discharge pressure of the pump. This will be much greater than 100 the pressure of the liquid in the annular pocket around the ring 12. For this reason the liquid leaking along the shaft past the ring 12 will be readily picked up, and sucked through the pipes 15 and delivered into the 105 pipes 14 to be returned to the suction side of the pump.

What I claim is:—

1. A centrifugal pump, having a casing containing a suction chamber and a discharge chamber, a pipe connecting said chambers through which fluid is forced 110

from the latter to the former, an impeller shaft having a bearing in the pump casing, an impeller fixed thereon, a fluid conduit leading from the shaft bearing and entering said pipe and formed into an ejector nozzle within said pipe.

2. In a centrifugal pump, a suction chamber, a discharge chamber, an impeller through which fluid is forced from the former to the latter, an impeller shaft to which said impeller is fixed, bearings in which said shaft rotates, a pipe connecting said chambers, a suction conduit leading from one of said bearings and entering said pipe whose end is formed into an ejector nozzle within said pipe.

3. In a centrifugal pump, a casing having a suction chamber and a discharge chamber,

an impeller through which fluid is forced from the former to the latter, an impeller shaft having bearings in the pump casing and to which said impeller is secured, a pair of pipes connecting said chambers, each pipe having a restricted suction, a pair of suction conduits leading from the shaft bearings and entering said respective pipes and whose ends within said pipes are formed into ejector nozzles which are turned toward said restricted sections.

In testimony whereof I have signed my name to this specification in the presence of two subscribing witnesses.

ARCHIBALD S. TELFER.
